UNITED STATES PATENT OFFICE.

MOULTON W. WHEELER, OF SAN DIEGO, CALIFORNIA.

SNARE FOR DRUMS.

1,207,825.

Specification of Letters Patent. Patented Dec. 12, 1916.

Application filed August 15, 1916. Serial No. 115,018.

To all whom it may concern:

Be it known that I, MOULTON W. WHEELER, citizen of the United States, residing at 3826 Seventh street, San Diego, in the county of San Diego and State of California, have invented certain new and useful Improvements in Snare for Drums, of which the following is a specification.

This invention relates to snares for drums and it has for its object the provision of a simple, inexpensive and improved article of this nature.

In the accompanying drawing Figure 1 is a plan view of a drum having my improved snare applied thereto. Fig. 2 is an under-side view of one end of the snare and, Fig. 3 is an edge view of one end of the snare.

Like numerals designate corresponding parts in all of the figures of the drawing.

Referring to the drawing 5 designates the body of the drum and 6 the lower head thereof.

My improved snare comprises a plurality of strands of spirally wound wire 7 of the usual and well-known form. These strands are brazed, soldered, welded or otherwise secured at their opposite ends to the plates 8 and 9. These plates are provided with angularly disposed, transversely slotted ends 10 and 11 and the slots of these ends receive non-elastic loops 12 of tape. These tape loops extend over the edges of the head 6 of the drum and are attached to any suitable type of straining devices, not shown, said straining devices forming no part of the invention. It is to be understood that any suitable type of strainer may be employed. By off-setting the ends of the plates 8 and 9, the loops are brought substantially into the plane of the wires 7.

A snare constructed in accordance with

the present invention has the advantage that all of the snares are stretched uniform and the operation of a single strainer imparts the desired tension to all of the wires or strands 45 7 at one time. The tape loops easily adjust themselves to the edge of the shell of the drum, the metal strands 7 not being required to be bent over the edge of the shell or over the edge of the head 6 as is the case 50 in some type of snares.

It is to be understood that the invention is not limited to the precise construction set forth but that it includes within its purview whatever changes as fairly come with 55 in the spirit of the appended claims.

Having described my invention what I claim is:

1. A snare for drums comprising a plurality of side by side metallic strands of like 60 length, a pair of transversely slotted plates to which said strands are fixedly secured and non-elastic straining loops passing through the slots of said plates, the combined length of the strands and the plates being less than 65 the diameter of the drum head upon which the snare is used.

2. A snare for drums comprising a plurality of strands, plates to which said strands are fixedly secured and straining 70 loops connected to said plates, said strands being of such length that the plates lie adjacent to the surface of the head of the drum when the device is in use and the tape loops extend over the edges of the head of the 75 drum.

In testimony whereof I affix my signature in the presence of two witnesses.

MOULTON W. WHEELER.
